US00D990299S

(12) **United States Design Patent** (10) **Patent No.:** **US D990,299 S**
(45) **Date of Patent:** **** Jun. 27, 2023**

(54) **BENDABLE FASTENER**

(71) Applicant: **Halliburton Energy Services, Inc.**,
Houston, TX (US)

(72) Inventors: **Minh Dang Nguyen**, Cypress, TX
(US); **Ricardo Ortiz**, Houston, TX
(US)

(73) Assignee: **Halliburton Energy Services, Inc.**,
Houston, TX (US)

(**) Term: **15 Years**

(21) Appl. No.: **29/746,889**

(22) Filed: **Aug. 18, 2020**

(51) LOC (14) Cl. **08-08**

(52) U.S. Cl.

USPC **D8/387**

CLAIM

The ornamental design for a bendable fastener, as shown and
described.

DESCRIPTION

FIG. 1 is an isometric view of a bendable fastener.

FIG. 2 is a front view of the bendable fastener of FIG. 1.

FIG. 3 is a rear view of the bendable fastener of FIG. 1.

FIG. 4 is a left view of the bendable fastener of FIG. 1.

FIG. 5 is a right view of the bendable fastener of FIG. 1.

FIG. 6 is an enlarged top view of the bendable fastener of
FIG. 1; and,

FIG. 7 is an enlarged bottom view of the bendable fastener
of FIG. 1.

The broken lines in the drawings illustrate portions of the
bendable fastener and form no part of the claimed design.

1 Claim, 7 Drawing Sheets
